SLUICE BOX RIFFLE

Perry Swedman, Seattle, Wash.

Application June 29, 1937, Serial No. 150,972

6 Claims. (Cl. 209--506)

My invention relates to a sluice box riffle. More particularly, my invention relates to a riffle to be positioned in the bottom of a sluice box to be used in mining operations for the purpose of separating precious metals from material which is lighter than said metals.

Such sluice boxes are commonly used in placer mining for gold, platinum and such like precious metals. Although I am herein describing my invention as particularly applied to placer mining for gold for purposes of definiteness and clearness, yet it is to be expressly understood that the invention is not to be limited to any such specific use, but is applicable to all uses where like conditions or problems exist in whole or in part, so far as the invention is applicable. Of course, the invention is applicable to the separation of bodies which differ in weight, even though they are not precious metals.

It is common practice to employ wooden riffles, but these wear out very rapidly and are objectionable in that rocks catch between adjacent riffle bars and in freeing them often the riffles are seriously damaged. It will be understood that gravel, including rocks of varying size, is run over the riffles in the sluice boxes and imposes a very severe wearing and grinding action upon the riffles. Attempts to overcome the objections to wooden riffles have been made by forming the riffles of metal, such as iron. But these soon wear and develop sharp edges, and become very difficult to handle at the time of "cleaning up the boxes", i. e., at the time when the riffles are raised to collect the gold or other valuable minerals which have been deposited between the riffles.

A primary object of my invention is to provide a riffle of which the wearing surface is formed of rubber.

Another primary object of my invention is to provide a riffle which is formed of two parts—a metal frame of bars and rubber elements adapted to be readily replaceable and releasably secured to said bars.

A further primary object of my invention is to provide a riffle which is highly resistant to the grinding and abrasive action of gravel, which will have a life a plurality of times longer than the wood and metal riffles heretofore in use, and which will not be seriously damaged by the removal of rocks which have lodged between adjacent riffle bars.

Also it is primary object of my invention to provide a riffle which will have a relatively large space in which concentrates may collect, and

which space may operate more effectively as a pocket which protects the metal concentrates against packing by the heavy stream of gravel passing thereover.

A further primary object of my invention is to have such wearing part formed of rubber, the elasticity of which, together with its form and with its manner of mounting, results in developing vibrations under the action of the stream of gravel passing thereover. The vibrating is particularly effective in causing fine gold particles to precipitate and collect behind said riffles.

A still further primary object of my invention is to provide a riffle which is economical in first cost and in maintenance, and which is characterized by being light in weight, as such riffles are often used in connection with dredges which are floatingly mounted, since it may be necessary to provide some eight hundred to one thousand of the riffle frames embodying my invention, which are preferably thirteen inches wide, and which are, of course, of the usual length to correspond with the width of the sluice box, which is about thirty inches as commonly employed in sluice boxes for dredges. In small dredges the width of the sluice boxes may be eighteen or twenty inches. The frames are preferably of aluminum.

A still further object of my invention is to provide a riffle of a character which is compressible and which will permit a wedging rock to be driven through the riffle without injury to the riffle.

A still further object of the invention is to provide riffle means comprising a frame of relatively strong and substantial material provided with cross bars, having readily applicable and readily detachable wear resistant resilient elements or caps of rubber or like material provided on the upper portions thereof, over which caps the sand and gravel pass.

The above mentioned general objects of my invention, together with others inherent in the same, are attained by the device illustrated in the following drawings, the same being preferred exemplary forms of embodiment of my invention, throughout which drawings like reference numerals indicate like parts:

Figure 1 is a plan view of a riffle section constructed in accordance with this invention;

Fig. 2 is a view partly in section and partly in elevation of the same taken substantially on dotted line 2—2 of Figure 1;

Fig. 3 is a transverse section on an enlarged

scale taken substantially on dotted line 3—3 of Figure 1, parts being shown in elevation;

Fig. 4 is a fragmentary detached perspective view of a portion of a riffle frame, parts being shown in section;

Fig. 5 is a fragmentary detached perspective view, with parts in section, of a rubber cap member as the same may appear when removed from the bars of the riffle frame;

Fig. 6 is a plan view of a modified form of riffle means constructed in accordance with this invention;

Fig. 7 is a sectional view on a larger scale, with parts in elevation, taken substantially on broken line 7—7 of Fig. 6;

Fig. 8 is a detached perspective view of a fragment of the frame member of the riffle device shown in Fig. 6;

Fig. 9 is a detached fragmentary perspective view of a piece of one of the rubber cap members used in the embodiment of the invention shown in Figs. 6, 7 and 8;

Fig. 10 is a view in cross section of a modified form of a rubber cap embodying my invention;

Fig. 11 is a view in cross section of a still further modified form of a rubber cap and rib of the metal frame embodying my invention.

Figs. 1 to 5, inclusive, show a preferred embodiment of the invention comprising a frame formed of two substantially parallel spaced apart side bars 10 and 11 and a plurality of substantially parallel transverse riffle bars 12. The side bars 10 and 11 are preferably of inverted L shape in cross section, as shown in Figs. 2 and 4. The riffle bars 12 have their end portions rigidly connected with the side bars, as by forming them integral with said side bars. These riffle bars 12 are preferably of substantially T shaped cross section with upright web portions which are narrow at their bottom edges and wider where they merge with the top flanges or head portions of the riffle bars. The under sides of the head portions of the riffle bars are preferably formed with upwardly concaved portions 13, which are hook shaped in cross section. The upper sides of the top flanges of the riffle bars 12 are preferably inclined, as shown in Figs. 3 and 4 and said upper sides are positioned below the plane common to the uppermost portions of the upper flanges of the side bars 10 and 11.

The rubber caps, elements or members 14, which are adapted to fit over the riffle bars 12 are each of rectangular cross section. The upper face portion 15 has downwardly extending side walls 16, which terminate in two depending gripping side flanges 17 that are separate from each other so as to leave the rubber cap member open along the bottom throughout its entire length. Passageways 18, corresponding in shape to the head portions of the riffle bars, extend throughout the length of the cap members and internal bead portions 19 are provided to engage within the hook shaped concave recesses 13 underneath the top flanges of the riffle bars 12. The rubber cap members are placed on the riffle bars 12 by spreading the flange portions 17 and side walls 16 apart and pressing the cap members over the top flanges of the riffle bars 12. The depending flanges 17 of the cap members fit closely against the upright web portions of the riffle bars 12. These flanges 17 are relatively thin and do not retard the vibration of the cap members and leave ample room between adjacent riffle bars for the collection of values.

The passageways 18 in the rubber cap members are preferably slightly larger than the head portions of the riffle bars 12 and fit somewhat loosely thereon so that the cap members are free to vibrate a limited amount as water and mineral bearing sand and gravel are passed over the cap members. It is found that this vibration of the cap members assists in the separation or precipitation of the gold and heavier minerals from the lighter sands and gravels. It will be understood that the passageway or recess 18 in the cap 14 may be of a size to render the cap tightly fitting to the bar 12. However, by providing the passageway slightly larger, a vibratory movement is permitted under the impact of the gravel striking the face or top portion 15 of the cap. It will be noted that the flanges 17 pinch inwardly. This inward pinching applies a pressure on the inclined face of the portion of the bar 12, and accordingly tends to support the caps 14 and permits a twisting or rocking movement under impact of the gravel passing thereover. This movement combines with the movement arising from the resiliency of the rubber to augment the vibratory movement of the cap as a whole.

These details relative to the passageway 18 being larger than the corresponding portions 12 of the bar over which the cap is to be placed and this pinching action of the flanges 17 are parts of my invention which are important and are provided in the preferred form. However, much of the advantage of my invention may be obtained without these features.

If the rubber cap 14 is provided with a passageway 18, which precisely fits the T part of the bar 12, and no pinching on inclined planes is provided by the flanges 17, still very important advantages of my invention remain. The mere resiliency of the rubber will provide for considerable vibration under the impact of the gravel and the long wearing quality of the rubber cap and the economy incident to its long wearing and ready replaceability and the forming of the riffle in two parts, viz., a metallic frame of light metal and replaceable rubber cap for the bars, still form important parts of my invention.

The water, together with the sand and gravel, pass over the riffles in the direction indicated by the arrows in Fig. 3. This flowing material is thus caused to cascade and eddy slightly and move in a downward direction as it passes off of the higher edge of each riffle cap and the heavier particles will continue this downward movement due to their greater inertia and will settle into the spaces between the riffle bars.

The riffle devices are made up in sections of convenient shape and size to be handled. These sections are usually placed in the bottom of a sluice box, not shown, and secured in any suitable manner. Any desired number of sections are used to secure the desired over-all length of riffle. The dimensions of the individual riffle bars and distance between bars may be varied. Satisfactory results have been obtained by making the cap members of from one to one and one-half inches across the top and by having spaces of from one to one and one-half inches between adjacent cap members. These cap members are very durable and highly resistant to abrasion by sand and gravel. The cap members are not costly and are very easy to replace in the event they do become worn. The metal frames are not subject to abrasion and will last practically indefinitely.

It will be remembered that mining operations are often carried on in sections of the country remote from transportation facilities so that it becomes a matter of great importance to provide elements of the operating equipment in a form which may be readily replaceable and thereby avoid reconstructing. The relatively light rubber caps or elements are not only strongly resistant to wear, so that they have a life a plurality of times longer than any other riffle commonly employed heretofore, but they are formed of material relatively light in weight so that maintaining them in their proper form for full operating efficiency is rendered comparatively simple and economical.

The cap members are elastic and stones which wedge between adjacent cap members can be displaced easily without damage to the riffles. Such stones may be readily driven downward as the side walls 16 are compressible and as the stone passes beyond these walls the opening diverges until the bars 12 are contacted. If they are not wedged in between the walls 16 of adjacently disposed rubber caps, then, of course, the stones may be lifted upwardly so that in either case they are readily removed without injury to the riffle bars.

The modified construction shown in Figs. 6 to 9 embodies an integral frame comprising spaced apart riffle bars 20 of approximately T shape in cross section. The lower sides 22 of the head portions of the riffle bars 20 and connector bars 21 are inclined upwardly from the outside toward medial planes of said bars to provide hook like means for engagement with inwardly directed bead portions 23 of rubber cap members 24. The rubber cap members 24 have longitudinal passageways 25 shaped to fit over the head flanges of the riffle bars 20 and also have transverse passageways 26 shaped to fit over the head flanges of the connector bars 21. The tops of the riffle bars 20 are not inclined but the tops of the cap members 24 may be inclined to obtain the same effect as hereinbefore explained in connection with the cap members shown in Figs. 1 to 5. The rubber cap members 24 are releasably secured and replaceable upon the bars 20 and the riffle device shown in Figs. 6 to 9 operates in substantially the same manner as the device shown in Figs. 1 to 5. Bars 21 have thereon short cap members 24'.

The modified construction shown in Fig. 10 illustrates a different form of flange 27.

The modified construction shown in Fig. 11 shows a still further form of cap 28 which is held upon the modified form of riffle bar 29 by screw means 30 in a countersunk recess 31 in the cap 28. I have discovered that it is important that the flanges 32 of cap 28 extend for a part of the distance down the bar 29. The eddying water, with its sand and gravel, causes a severe wearing along the upper portions of the bar 29 so that protection is necessary.

Obviously, changes may be made in the forms, dimensions and arrangement of the parts of my invention, without departing from the principle

thereof, the above setting forth only preferred forms of embodiment.

I claim:

1. A riffle comprising a metal frame member having cross bars of a T form in cross section; and a resilient rubber cap member having a recess of a T form cross sectionally considered engageable with said cross bars.

2. Riffle means of the class described, comprising spaced apart riffle bars; and resilient rubber cap members removably secured to said riffle bars,—said cap members covering the upper portions of said riffle bars and providing an opening therebetween with diverging sides, whereby rocks which become lodged between said caps may be readily dislodged downwardly.

3. Riffle means of the class described, comprising spaced apart normally horizontal riffle bars having upper edge portions of enlarged cross section; and resilient rubber cap members having longitudinally extending internal recesses fitting over and releasably receiving the enlarged upper edge portions of said riffle bars providing readily renewable abrasive resistant caps for said riffle bars.

4. Riffle means of the class described, comprising spaced apart normally horizontal riffle bars having upper edge portions of enlarged cross section; and resilient rubber cap members extending substantially throughout the length of said riffle bars, said cap members having longitudinally extending internal recesses open along one side of the cap members and fitting over and receiving the enlarged upper edge portions of the bars, the side walls of the cap members being flexible whereby the cap members will vibrate on the riffle bars when material and water is passed thereover, said recesses being larger than the enlarged upper edge portions of the bars whereby said cap members will vibrate on the riffle bars when material is passed thereover.

5. Riffle means of the class described, comprising spaced apart normally horizontal riffle bars of substantially T shaped cross section having upper head flanges which are undercut on their lower sides providing portions of substantially hook shaped cross section; and resilient rubber cap members having longitudinally extending internal recesses open along one side of the cap members and corresponding in shape to the head portions of said T shaped riffle bars, said cap members having head portions engaging beneath the hook shaped portions of said riffle bars removably securing the cap members to the riffle bars.

6. Riffle means of the class described, comprising spaced apart normally horizontal riffle bars having upper edge portions of enlarged cross section; and resilient rubber cap members having longitudinally extending internal recesses fitting over and releasably receiving the enlarged upper edge portions of said riffle bars providing readily renewable abrasive resistant caps for said riffle bars, and having depending side flanges which pinchingly hold the cap to said bars.

PERRY SWEDMAN.
